UNITED STATES PATENT OFFICE.

JAMES F. ZION, OF PHOENIX, ARIZONA.

ORE-CONCENTRATOR.

1,052,301.

Specification of Letters Patent. Patented Feb. 4, 1913.

Application filed August 3, 1911. Serial No. 842,943.

To all whom it may concern:

Be it known that I, JAMES F. ZION, a citizen of the United States, residing at Phoenix, in the county of Maricopa and State of Arizona, have invented new and useful Improvements in Ore-Concentrators, of which the following is a specification.

The present invention relates to certain novel and useful improvements in ore concentrators, and has particular application to a device of the class described adapted especially for the concentration and separation of dry ores.

In carrying out my invention, it is my purpose to provide a concentrator which will embrace the desired features of cheapness and simplicity, and which will effectually and conveniently separate the valuable ore from the waste or dirt with which the ore is mixed.

It is also my purpose to provide a structure in which the material to be concentrated is introduced to the separator through a tube and acted upon by a blast from a fan, particles of ore dropping into various pockets according to their specific gravity while the tailings or waste are carried by a second fan to a point of discharge.

With the above-recited objects and others of a similar nature in view, the invention consists in the construction, combination and arrangement of parts, set forth in and falling within the scope of the appended claims.

In the accompanying drawing:—Figure 1 is a view in side elevation of an ore separator embodying my invention. Fig. 2 is a longitudinal sectional view. Fig. 3 is a top plan view. Fig. 4 is an end view.

Referring now to the accompanying drawings in detail, the numeral 1 indicates the casing or body of the concentrator which is provided preferably adjacent to one end with a hopper 2 through which the ore is fed into the body of the casing, the latter being provided at its bottom with a series of pockets 3 preferably V-shaped in form which may be higher at the back end so as to concentrate while sliding out by gravity. Arranged at one end of the trough is a housing 4, for the fan or blower 5, the latter being mounted upon the power shaft 6, which is driven by means of the variable speed pulley 7, the outlet of the fan 8 discharging the blast into the chamber 1 directly beneath the hopper and against the material passing from the hopper to the

casing. At the opposite end the casing is formed with a spiral shaped conduit 9 gradually reducing or tapering in diameter toward the end 10, which end communicates with the house 11 of the suction fan 12, the latter drawing the tailings or waste, which is relatively lighter in its specific gravity than the ore through a conduit and directs the same to the discharge tube 13, which is also preferably provided with a series of pockets 14 to catch any particles of ore which may be contained in the tailings or waste. The waste is directed through the end of the discharge conduit to any suitable point of deposit.

From the above description, taken in connection with the accompanying drawings, the construction and operation of my improved concentrator will be readily apparent. The fan is started at the desired speed and the material is dumped into the hopper 2 passing thence into the casing or chamber 1. As the material falls in the casing, the blast of air from the fan strikes the same and the particles of material are driven along through the casing, and drop into the tanks at the bottom of the casing according to their specific gravity. The suction fan on top of the casing draws the lighter material such as the tailings or waste through the spiral conduit and forces such tailings through the discharge tube 13, any particles of ore which may be mixed with the tailings dropping into the pockets in said discharge tube while the waste is discharged through said tube.

The exhaust fan is mounted upon the shaft 15 which is driven by the variable speed pulley 16 which may receive power from any suitable source such as a belt or the like.

It will be noted that I provide an exceedingly simple yet efficient concentrator for separation of ore from the dirt or gangue with which it is mixed, and, furthermore, it will be noted that the construction being very simple may be manufactured and marketed at a relatively low cost, thereby making it especially available for use in connection with small mining properties, where the use of large complicated expensive machinery would be prohibited owing to its cost in installation and working.

I claim:

In an ore concentrator, the combination of a casing, pockets in the bottom of said cas-

ing, a feed hopper for the material leading into the upper side of the casing, near one end thereof, a pressure blower communicating with the casing at one end thereof adjacent the feed hopper and adapted to discharge a current of air against the material falling into the casing from the said hopper, a spiral conduit connected to the end of the casing opposite from the pressure blower and in alignment therewith, a suction fan mounted upon the upper surface of the casing, a housing for said fan, connections between said housing and spiral conduit where-

by the tailings from the mass of material are drawn through the spiral conduit to the 15 housing by means of the fan, and a discharge conduit leading from said housing and provided with a plurality of pockets substantially as and for the purpose set forth.

In testimony whereof I affix my signature in presence of two witnesses.

JAMES F. ZION.
